UNITED STATES PATENT OFFICE.

RUDOLPH M. HUNTER, OF PHILADELPHIA, PENNSYLVANIA.

DYNAMO-ELECTRIC MACHINE.

SPECIFICATION forming part of Letters Patent No. 397,550, dated February 12, 1889.

Application filed July 14, 1888. Serial No. 279,942. (No model.)

To all whom it may concern:

Be it known that I, RUDOLPH M. HUNTER, of the city and county of Philadelphia, and State of Pennsylvania, have invented an Improvement in Dynamo-Electric Machines and Motors, (Case 63,) of which the following is a specification.

My invention has reference to dynamo-electric machines and motors; and it consists of certain improvements fully set forth in the following specification and shown in the accompanying drawings, which form part thereof.

Much loss has been experienced from use of dead wire on the armatures of dynamo-electric machines and motors, and this is so not only in ring or Gramme armatures, but exists also in the drum or Siemens armature. Many ways have been devised to lessen the effect of the useless and objectionable resistance of this dead wire in the armature, and particularly so in the case of the Gramme ring. It has been clearly proved that in the Gramme ring when the iron core was not saturated the wire on the inside of the ring was absolutely screened and acted simply as a resistance. No current is generated in it, and its function is simply as a conductor. When the low resistance of the armature is of importance, it is perceived that the dead wire is considerable of an objection. When the core of the armature is fully saturated and the magnetic lines of force pass through it to find their way to the opposite pole of the machine, the induction effect on the moving wire is such that it produces a current in the inside wire in the reverse direction to that produced in the outer coils by the field-magnets. This reverse current reduces the efficiency of the machine, and is therefore very objectionable.

My invention, so far as the armature is concerned, relates to the Gramme ring and is directed to improve the efficiency of the machine by utilizing the wire upon the internal surface of the armature-ring. It has been proposed to revolve a Gramme armature-ring on the poles of the field-magnets, so that the annular ring formed by the armature fits into curved grooves in the north and south pole-pieces of the field-magnets. This arrangement, however, has much objection in its mechanical constructions and necessitates the

employment of a very short armature. It has also been proposed to support a field-magnet within the armature and allow it to remain stationary by action of gravity while the armature revolved; but this is very objectionable in practice from a mechanical point of view, and also because the looseness of the support of the internal field-magnets would render the magnetic condition of the armature unstable and necessitate constant watching of the brushes at the commutator.

In carrying out my invention, so far as it relates to the armature, I construct my armature like an ordinary Gramme ring, only I make it long, and inside of this I place a second ring with coils to form an internal field, and this latter ring may be wound like a Gramme or a drum armature. Both of these rings are secured to the same frame and revolve together as an integral piece of apparatus. The external field may be of any construction. I may connect the armature and internal field-coils in series or parallel, the latter being the simplest and requiring only one commutator. The coils on the armature and internal field are the same in number and are connected to the same commutator-sections, only the coupling up of the internal field is such as to bring its north and south poles at right angles to the north and south poles of the armature, or thereabout, and so as to correspond with the fixed external poles. The operation is such that as the armature and internal field-coils rotate their poles shift also, and the internal field magnetizes the internal wire of the armature and greatly increases its inductive effect, and enables heavier cores to be used. This is particularly advantageous in motors, where with a small motor we can obtain a large torque at slow speed. The field-magnets may be wound with coils suitable for a series machine or shunt or compound machine. It is evident that by winding a series coil on the external field and in series with the armature and internal field, and with an external long shunt coil around both the internal field, armature, and series field-coil, a very sensitive self-governing motor may be made by properly proportioning the resistances. It is essentially the combination of the windings of long and short shunt machines, and the law

of winding is peculiar and different from that of any other machine. The internal field and the stationary shunt-coils of the external field may be parallel and both in rotation 5 with the armature as short shunts. There are many modifications to the winding of this machine.

The field-magnets I form of horseshoe shape and in sections to reduce as far as possible 10 heating and losses due to Foucault currents. These sections I prefer to make of good malleable iron or cast-steel, and the two opposing horseshoe-magnets are brought face to face with the only dividing lines through them in 15 the center of the north and south poles and where such breaks are not injurious. The metal is continuous from pole to pole, and no joints or yoke-pieces are used at all. The sections of these field-magnets are bolted together 20 and to standards at each end of non-magnetic material in which the armature-shaft is supported by suitable bearings. These sections have lateral contact-pieces which hold them apart and form ventilating-spaces 25 or passage-ways between them, not only at the polar-extensions, but also at the cores. In the winding of the field-magnets I prefer to interpose a winding of iron or steel wire on top of a coil of insulated copper wire and 30 under another coil of the latter to increase the strength of the field. The armature and internal field-coils I may also wrap in this manner with soft and well-annealed iron wire, forming an iron shell upon the outside or inside, or both, of the armature.

There are many other features of construction, more fully set out hereinafter, which are not so important as those above referred to.

In the drawings, Figure 1 is a plan view of 40 a dynamo-electric machine or motor embodying my invention with the coils removed. Fig. 2 is an end view of same. Fig. 3 is a cross-section of same on line $y-y$. Fig. 4 is a longitudinal sectional elevation of same on line 45 $x-x$. Fig. 5 is a sectional elevation of a portion of the armature and internal field-magnets with the coils. Fig. 6 is a cross-sectional elevation of same on line $z-z$, with part of the coils removed. Fig. 7 is an elevation of the 50 armature removed. Fig. 8 is an end elevation (with part in section) of the external field-magnets. Fig. 9 is a perspective view showing two sections of the field-magnet. Fig. 10 is a sectional view of a portion of the brush-holder. Fig. 11 is a cross-section of same at 55 its support concentric with the armature-shaft. Fig. 12 is a diagram illustrating one method of coupling up the coils of the armature and internal field in parallel. Fig. 13 is 60 an illustrative drawing showing the connection of the external and internal fields in series with the armature. Figs. 14 and 15 are diagrams showing how the coils of the motor may be coupled up with a variable field-resistance. Fig. 16 is a diagram illustrating 65 my preferred winding for shunt-wound motor employing a series coil and long and short

shunt field-coils. Fig. 17 is a perspective view of one of the core-segments for the armature and internal field, and Fig. 18 is a diagram 70 showing a modified winding of my machine.

A A represent two horseshoe field-magnets having their polar extensions brought end to end, (see Figs. 3 and 8,) and each of these horseshoe-magnets is preferably made up of 75 sections A' and A², having bearings or distance projections a a', which hold said parts sufficiently separated, as at C, to allow free passage of air through both the core and polar extensions and yet allow them to be bolted 80 firmly together to constitute a single structure. It will be noticed that the only break in the continuity of the magnetic metal or belt of the field is directly in the center of the polar-pieces and where it is not objectionable. The metal at these adjoining places is recessed, as at a², and when the sections 85 of the core are put together such recessed portions form the ventilating-apertures c, which are continuations of the ventilating- 90 spaces C between the sections A' A².

D D are two end standards having feet and formed of brass, gun-metal, or other non-magnetic material, and these standards are bolted to the two horseshoe-cores A A by means of 95 the four bolts B, and with distance-pieces b between them and the cores. This holds the cores firmly in position and makes the entire structure as solid as if cast integral, and at the same time keeps the parts so separated 100 that free ventilation and access can be had. The horseshoe-cores have the sections A' different from the outside or end sections, A², which are made to enlarge at the polar extensions to form a larger armature-space and allow of an armature of considerable length.

The field-coils are wound about the vertical parts of the cores, and are kept in place by the brackets or flanges O, of brass, bolted to the outer parts of the cores. They are made 110 of brass or non-magnetic material to prevent the dissipation of the magnetic lines of force.

It is evident that while I prefer to make the sections of my external field-magnets of malleable iron, they may be made of wrought-iron forged or when rendered fluid with aluminium, or they may be of cast-iron. Broadly considered, these horseshoe-shaped magnets may be of solid wrought-iron not in sections; but I prefer to make them as shown.

D' and D² are end bearings for the armature-shaft E and are secured to the standards D, as shown. The bearing D' is supported away from the standard, so as to form the commutator-space. The inner and adjacent parts of the field-cores are curved, as at A³, to form the circle for the armature. (See Figs. 3, 8, and 9.)

The constructions of the armature and internal field are clearly shown in Figs. 3, 4, 5, 6, 7, 12, and 17. Secured upon the armature-shaft at each end of the field-pieces are the armature-frames F, of brass. Connecting these two frames are rods f and f', upon which are

the core-rings L and K, (see Figs. 6 and 17,) forming two concentric rings, each formed of thin quarter-sections of thoroughly-annealed iron. These sections are stamped out to make them uniform, and are preferably without polar projections, so as to give more available space for wire. The outer ring, K, is much heavier than the internal ring, L, which latter is the core of the internal field. The two rings so formed are wound with coils of wire, preferably of the same number of coils, but with different numbers of turns, as the ampère turns or windings *l* on the core L, when in shunt relation to the armature-coils *k*, will be very different and dependent upon the resistance necessary. If the commutator G has forty-eight sections, then there are forty-eight coils or sections of coils *k*, and also forty-eight coils *l*, and these are coupled up in parallel, as shown in Fig. 12—that is to say, the armature-coils *k* and field-coils *l* are so connected as to cause the north and south poles of the field-magnets to be at right angles or substantially at right angles to the similar poles of the armature. When such armature and internal field magnets are hung in position in the stationary field-magnet, the internal field-poles will correspond with the external field-poles.

Another point which it is well to refer to is that the generating capacity of the armature is dependent upon the speed of its wire through the field, and for a given wire on the armature and speed of travel through the field the strength of the field must be predetermined. Now the wire on the interior of the armature would have a much less speed than that upon the outside, and consequently the internal field must be so wound as to produce in the internal wire the same current as produced in the external wire.

If desired, the internal field-coils and armature-coils may be each wrapped with a covering magnetic wire—such as indicated at *m* M—of well-annealed soft iron; but, if desired, either or both of such wrappings may be dispensed with.

G is the commutator, and may be made in any way desired. In the construction in which the internal field is in shunt relation to the armature-coils each section of the commutator is coupled to one coil of the armature and one coil of the internal field, as shown in Figs. 12 and 16, which brings the poles of the said armature and internal field at right angles with each other.

In the modification shown in Fig. 13 we have the two field-coils and armature in series employing two commutators, *G* and *G'*, (the armature K and internal field, L, being separated for clearness.) The brushes *g* are held in a suitable spring-clamp, *I*, so as to press upon the commutator. These clamps are carried upon an adjustable arm, *H*, journaled on a boss, *N*, concentric with the armature-shaft *E* and having an annular groove, *n*. Carried by the arm *H* is an adjusting-handle, *J*, which

has its end screw-threaded, and is adapted to be turned to enter the annular groove *n* and hold the arm *H* in any desired position to 70 which it may be adjusted. The arm *H* has one of the brushes positively fixed to it at one end, and its other end has a slot, *h*, in which the other brush is adjustably secured. This will admit of sufficient adjustment of 75 the brushes relatively to each other, and the adjustability of the arm *H* by handle *J* will permit of the simultaneous adjustment of both brushes. These parts are shown in Figs. 1, 2, 4, 10, and 11.

The external field-coils may be wound in any suitable manner. As shown, I have two sets of coils, *P* and *P'*. In Figs. 8, 14, and 15 these coils are shown as of the same resistance and coupled up in Fig. 14 for series and 85 in Fig. 15 for parallel to vary the field resistance. In addition to this there is shown between these coils a third coil, *p*, of iron or steel wire, which may be insulated or not, as desired, to increase the field strength; and the 90 current may be shunted through these coils for an instant at starting to produce a reactive or inductive action to quickly start the machine. *Q* is a switch in the circuit *r* for cutting these coils *p* out of circuit. There is 95 one of the coils *p* on each magnet, and these may be coupled in series, Fig. 14, or parallel, Fig. 15, the former being preferred.

In Figs. 14 and 15, *S* and *S'* represent the terminals of the machine, and *R* the motor- 100 circuit or the connections on the machine between the coils.

Referring now to Fig. 16, we have the armature constructed as before; but in this case the coils *P* are made shunt-coils of high resistance in a shunt-circuit, *R'*, around the terminals of the machine constituting a long shunt, whereas the coils *P'* are of low resistance and in series with the armature. It will thus be seen that in this construction we have 110 a compound machine combined with the internal field shunt-coil of the short-shunt type, forming a shunt only to the armature. In Fig. 18 we have the same winding with the exception that the external field long shunt is 115 converted into a short shunt.

It is evident that the coils *p* may be used with the winding shown in Figs. 16 and 18, if desired. This machine is equally adapted as a generator or motor. For traction purposes 120 the motor should be wound as a series machine; but for stationary work on constant potential circuits it is best as a double shunt or combined long and short shunt compound machine on account of it being made self-regulating.

While I have shown the most desirable form of parts and constructions, I do not limit myself to the details, as they may be modified in various ways without departing from the 130 spirit of my invention.

Having now described my invention, what I claim as new, and desire to secure by Letters Patent, is—

1. In a motor or dynamo-electric machine, the combination of stationary field-magnets, a rotating armature, and internal field-magnets located and secured within the armature, so as to rotate therewith.
2. In a motor or dynamo-electric machine, the combination of stationary field-magnets, a rotating armature, internal field-magnets located and secured within the armature, so as to rotate therewith, and a commutator common to both the armature and internal field-magnets.
3. In a motor or dynamo-electric machine, the combination of stationary field-magnets, a rotating armature, internal field-magnets located and secured within the armature, so as to rotate therewith, and connections between the coils of the armature and internal field-coils, whereby they are coupled in parallel.
4. In a dynamo-electric machine or motor, the combination of a shaft, an armature secured to said shaft, concentric supplemental field-magnets also secured to said shaft and having a fixed mechanical relation with respect to the armature, and electrical connections between the coils of the armature and field-magnets.
5. The combination of a shaft, an armature secured to said shaft, concentric field-magnets also secured to said shaft and having a fixed mechanical relation with respect to the armature, electrical connections between the coils of the armature and field magnets, and a stationary field-magnet independent of the armature, having one or more of its coils in series with the armature.
6. In a dynamo-electric machine or motor, the combination of a ring-armature, a circular supplemental field-magnet core having the same number of magnetizing-coils as the armature, a commutator having as many sections as coils in the field-magnet or armature, and connecting-circuits between the commutator sections, armature, and said field-coils, whereby the poles of the field-magnet shall be at right angles or substantially at right angles to the poles of the armature.
7. The combination of stationary field-magnets, a rotating armature, and rotating field-magnets concentric with said armature, connecting-circuits, and a commutator for changing the poles of the rotating field-magnets with a speed commensurate to that of its revolution.
8. The combination of a shaft, an armature-core, and internal field-magnets secured to and carried by said shaft, a stationary external field-magnet, and coils on said armature-core and internal field-magnets in which the resistance of the armature-coils is very low and the resistance of the internal field-coils is relatively very high.
9. The combination of a shaft, an armature-core, internal field-magnets secured to and carried by said shaft, a stationary external field-magnet, coils on said armature-core in which the resistance is very low, coils on the internal field-magnets in which the resistance is relatively high, and a commutator having its sections connected each to one of the high and one of the low resistance coils.
10. In a dynamo-electric machine or motor, the combination of a shaft, non-magnetic frames secured to said shaft, an armature-core and a supplemental internal field-core, both secured to and between said non-magnetic frames so as to be rigid with respect to each other, and coils upon each of said cores.
11. The combination of an armature and internal field-magnets built as one structure and rotating at the same speed, in combination with a supporting-shaft, two external field-magnets of the horseshoe type, having their poles arranged toward each other, non-magnetic standards at each end of the machine, having bearings for the shaft, and bolts for uniting the external field-magnets to the standards and in fixed relation to the armature and internal field-magnets.
12. The combination of an armature and internal field fixed thereto and having their coils arranged in parallel, and an external field having a coil also arranged as a shunt with respect to the armature-coils.
13. The combination of an armature and internal field fixed thereto and having their coils arranged in parallel, an external field having a coil also arranged as a shunt with respect to the armature-coils, and a second coil connected in series with the armature.
14. The combination of an armature and internal field fixed thereto and having their coils connected in parallel and the internal field-coil arranged as a short shunt with respect to the armature, an external field having a coil connected in series with the armature, and a second coil connected as a long shunt around the armature and series field-coil.
15. In a dynamo or motor, the field-magnets having two coils, with a third coil of magnetic metal wound upon the field and interposed between said field-coils.
16. In a dynamo or motor, the field-magnets having two coils, with a third coil of magnetic metal wound upon the field and interposed between said field-coils, and a circuit for passing part of the current which energizes the machine through said coil of magnetic metal.
17. In a dynamo or motor, the field-magnets having two coils, with a third coil of magnetic metal wound upon the field and interposed between said field-coils, a circuit for passing part of the current which energizes the machine through said coil of magnetic metal, and a switch to cut said coil out of circuit.
18. In a dynamo or motor, a field-magnet formed of a series of U-shaped sections separated to form air-spaces between them, in combination with an armature and its shaft, end standards having bearings for said armature-shaft, and bolts for clamping

said sections together and to the end standards.

19. In a dynamo or motor, a field-magnet formed of a series of **U**-shaped sections 5 separated by distance-pieces formed integral with them to form air-spaces between them, in combination with an armature and its shaft, end standards having bearings for said armature-shaft, and bolts for clamping said 10 sections together and to the end standards.

20. A field-magnet consisting of the heavy cast sections $A' A^2$, having the distance-pieces $a a'$, forming ventilating-spaces C , in combination with the bolts B , passing through the 15 polar extensions to unite said sections together.

21. In a dynamo or motor, the combination of two oppositely-arranged horseshoe-shaped magnets brought close together in the central 20 lines of the poles of the machine, standards at each end, and long clamping-bolts to unite the magnets rigidly together and to the standards.

22. In a dynamo or motor, the combination 25 of two oppositely-arranged horseshoe-shaped magnets formed of a series of heavy sections and having their polar extensions brought close together in the central lines of the poles of the machine, standards of non-magnetic metal at each end, and long clamping 30 bolts to unite the magnet-sections rigid together and to the standards.

23. In a dynamo or motor, the combination 35 of two oppositely-arranged horseshoe-shaped magnets brought close together in the central lines of the poles of the machine, standards at each end, long clamping-bolts to unite the magnets rigidly together and to the standards, an armature, and an armature-shaft 40 journaled in said standards.

24. The combination of two oppositely-arranged horseshoe-shaped magnets having integral polar extensions made long and brought together in a line corresponding to the center 45 of the two poles of the machine and a frame or frames for uniting said field-magnets together to form the armature-space.

25. The combination of two horseshoe-shaped field-magnets having integral polar 50 extensions and brought together to form continuous or practically-continuous north and south poles for the armature, end frames or standards having bearings for the armature-shaft, long bolts which extend through the 55 four polar extensions and unite the standards thereto into a rigid structure, an armature rotating within the space bounded by the polar extensions, and an armature-shaft journaled in the standards.

60 26. The combination of two horseshoe-

shaped field-magnets formed of cast sections divided in the direction of their length and having their polar extensions made integral and brought together to form continuous or practically continuous north and south poles 65 for the armature, end frames or standards having bearings for the armature-shaft, long bolts which extend through the sections of the four polar extensions and unite the standards thereto into a rigid structure, an armature 70 rotating within the space bounded by the polar extensions, and an armature-shaft journaled in the standards.

27. The combination of two oppositely-arranged horseshoe-shaped field-magnets without yoke-joints and formed in sections of 75 ductile magnetizable metal and having their polar extensions made integral and brought together in the central lines of the poles of the completed machine, thereby forming a substantially continuous magnetic band around the armature, with two joints diametrically opposite and in line with the centers of the poles of the machine.

28. A field-magnet section formed of horseshoe shape and of magnetizable metal, with the separating projections $a a'$ and the curved face A^3 to form the armature-space. 85

29. An integral field-magnet section formed of horseshoe shape and of malleable iron, with 90 the separating projections $a a'$ and the curved face A^3 to form the armature-space.

30. The combination of two horseshoe-shaped field-magnets formed in sections of malleable iron and uniting to form the armature-space, two end standards of non-magnetic material, bolts for holding the sections of the field-magnets and standards rigidly together, and an armature and its shaft journaled in the standards. 95

31. The field-magnets $A A$, made horseshoe shape and formed of sections $A A^2$, having air-spaces $C c$ between them and having their polar ends brought together, as set out, end standards, D , of non-magnetic material, having bearings, bolts B , extending through the sections $A' A^2$, and standards to unite them all into a rigid structure, an armature, and its shaft journaled in the standard-bearings. 105

32. The combination of an armature and an internal field-magnet with a wrapping of magnetic metal between the armature and field windings. 110

In testimony of which invention I hereunto set my hand.
